DESIGN FOR A COMBINATION DRIVER'S LICENSE RECEPTACLE AND KEY CHAIN

Martin E. Trolle, St. Paul, Minn., assignor to
Brown & Bigelow, St. Paul, Minn., a corpora-
tion of Minnesota

Application September 7, 1940, Serial No. 94,846

Term of patent 14 years

To all whom it may concern:

Be it known that I, Martin E. Trolle, a citizen of the United States, residing at St. Paul, county of Ramsey, and State of Minnesota, have invented a new, original and ornamental Design for a Combination Driver's License Receptacle and Key Chain, of which the following is a specification, reference being had to the accompanying drawing, forming part thereof:

Figure 1 is a perspective view of a combination

driver's license receptacle and key chain, shown in closed position and illustrating my new design.

Figure 2 is a perspective view of the same with the license receptacle in open position, illustrating my new design.

I claim:

The ornamental design for a combination driver's license receptacle and key chain, as shown and described.

MARTIN E. TROLLEN.
